UNITED STATES PATENT OFFICE.

GEORGE EUGENE MITTINGER, OF CLEVELAND HEIGHTS, OHIO.

METALLIC HEAD FOR WOODEN KEGS AND THE LIKE.

Application filed May 26, 1926. Serial No. 111,783.

This invention relates to improvements in metallic heads for wooden kegs and the like and a method of producing the same and is an improvement on my U. S. Patent, No. 5 1,517,087, dated November 25, 1924.

The primary object of my present invention is to stiffen the improved head by means of radiating portions to receive the shock of the package when it should be dropped from 10 a railroad platform or other place. The receptacle or package is for the purpose of containing nails, bolts, nuts, rivets, etc., that are to be transported from place to place. It is found that such packages are frequently 15 dropped sometimes from quite an elevation and the package when it strikes is most likely in such a position that the shock is received on the head, or at the head of the package. The shock causes an outward pressure on the 20 head, and it is the object of the present invention to prevent the head from being bent outward by the shock, or in extreme cases the head displaced or partially displaced. Should the head be displaced, its contents fall 25 around and pile up and must be removed.

After a series of experiments and tests, I have succeeded in so improving the head that it is stiffened sufficient to fully withstand the endwise shock due to the dropping 30 of the package as above stated.

I have also devised the present improvements in a manner which will prevent the package from being moved out of a true circle by the shock, thus maintaining the head 35 within the receptacle at all times during transportation, which will stand the extreme rough use to which such receptacles are subjected.

I accomplish the foregoing results by 40 forming in the horizontal portion of the head a plurality of double stems that radiate from substantially the center of the horizontal portion, whereby the head is prevented from being distorted out of a true circle and therefore prevented from being displaced or partially displaced by means of a shock.

Other objects of the invention will appear 45 from the following description thereof to which reference is made.

50 In the accompanying drawings:

Figure 1 is a top perspective view of my improved metallic head.

Figure 2 is an end or bottom perspective view of my improved head.

55 Figure 3 is a central vertical sectional view

of the improved head applied to a wooden keg.

Figure 4 is a central sectional view of the finished article.

I wish it understood that although I refer 60 to the article as a head for kegs, it can apply to both ends of a keg, that is it will form a head for the bottom or the top or both ends of the keg, and therefore in using the term "head" it includes both ends of the 65 receptacle.

My improved head comprises a peripheral portion 1 which is made substantially U-shaped in cross section. By this is meant that it has an outer flange 2 and an 70 inner flange 3, and the inner flange connected at its lower end by a transversely arranged integral portion 4 that makes a closure for the keg. Thus far I have described only what is disclosed in my aforesaid patent. 75

Coming now to the improvement so far as the article herein is concerned, it consists in forming in the horizontal portion 4 radially arranged doubled portions or ribs 5. Attention is particularly directed to the fact 80 that these portions 5 extend substantially from the lower edge of the inner flange 3 to substantially the center of the horizontal portion 4. While I do not show these ribs extending to the center of the head 4, I wish 85 it understood that they may so extend without affecting the present invention. In the form here shown I leave a small circular part 6, because it serves a good place for stamping a number in the keg, the contents of the keg, and because the center portion is so small that it withstands any 90 inward push that may occur by reason of a shock. As just stated, however, they may extend no further than here shown 95 but may extend substantially to the center.

These radially extending ribs are pushed downward and in cross section they form a U-shape as shown at 7 in Figure 4, for being pressed together or substantially together as 100 shown. It will be understood that these ribs when so formed are very stiff, so far as endwise pressure is concerned. Since these ribs are arranged radially in respect to the head, they will receive the shock irrespective of 105 the exact point the shock may occur, exactly as the spokes of a wheel so far as resisting the pressure due thereto.

Attention is also directed to the fact that the outer ends 8 of these ribs 5 taper, as do 110

also their inner ends 9. By reason of these tapered ends, the outwardly expanded portion 11 that fits into the inner groove 12 of the staves 13 of the receptacle can be 5 moved by hammering down on the central portion 6, or upon any part between the outer ends 8 and the inner ends 9. By hammering the said horizontal portion downward, the expanded part 11 will be withdrawn 10 from the groove 12 in a manner substantially as shown in Figure 3 of my patent hereinbefore mentioned.

From the foregoing it will be seen that a head with the present improvement is adapted 15 to withstand a sidewise shock such as these packages receive many times in transportation without the head being thrown out of circle, and therefore without its position being disturbed.

20 In forming this head with these radiating ribs approximately 25 or 50% necessary metal for forming the ribs is provided by a stretch of the metal, while the other 75 or 50% is provided by the upward bulged 25 portion.

I desire it to be understood that modifications and variations may be made in the invention above described without departing from the spirit of the invention so long as 30 the modifications are within a fair interpretation of the appended claim.

When the ribs 5 are compressed until their adjacent walls are in engagement, thus forming ribs which will withstand severe

strains from within the keg, then it is necessary to curve the ends of these ribs 5 as shown at 8 and 9 in order to enable the head to be depressed sufficiently to withdraw the outwardly expanded portion 11 from the groove 12.

Having thus described my invention, what I desire to claim and secure by Letters Patent is:—

An attachable and detachable metallic head for wooden kegs and the like comprising a wood body having at its inner side near one end an annular groove, a metallic head having an outwardly extending U-shaped periphery embracing said end of the keg, the inner wall of the U-shape expanded outwardly into said groove and the horizontal portion of the head provided with a plurality of downwardly and radially extending doubled closely compressed ribs with their adjacent walls in engagement, the said walls forming substantially one for sustaining pressure from within by the contents of the keg, both ends of the ribs gradually tapered downwardly in easy curves in a line with the said head to permit the head to be depressed, whereby the said head will withstand inward pressure and can be depressed downwardly for the purpose of withdrawing the expanded portion from the groove formed in the said keg.

In testimony whereof I hereunto affix my signature.

GEORGE EUGENE MITTINGER.
